CHAIR

Carlyle F. Streit, Cincinnati, Ohio

Application July 10, 1940, Serial No. 344,762

3 Claims. (CL 155—73)

This invention relates to chairs and is particularly directed to that type of chair known as a reclining or easy chair. More particularly, the invention is directed to improvements in this type of chair relating to adjustment of the angle at which the chair inclines and to means for converting the chair to a rocking type.

Frequently, the person occupying a chair desires to change the degree of inclination of the chair. In the past, it has been necessary to, first arise from the chair, thereafter, raise or lower the back of the chair and, finally secure the back in adjusted position by means of ratchet devices, etc.

Accordingly, it has been an object of the present inventor to provide for vertical adjustment of the height of the rear of the chair, and thus the amount of recline, through means which is operable while the occupant is still seated in the chair. By means of the present invention, this adjustment is brought about by pressure exerted in a rearward horizontal direction while the person is still seated in the chair but with the person's weight taken from the chair to some extent. In other words, the normal relaxed or dead weight of the occupant will not operate the device inasmuch as a direct rearward shifting pressure is required.

It has been a further object of the present inventor to provide this device as a part of the normal rear leg structure of an easy chair whereby the appearance of the chair in one position is conventional. In conjunction with this objective it has been the purpose to so embody the adjustable element that it is more or less hidden from view and therefore does not detract from the appearance of the chair.

It has been a further object of the inventor to provide a device capable of movement to alternate positions of recline for the chair, which device, in one position, constitutes a rocker, converting the chair from a stationary reclining type to a rocker type. It is so arranged that the device is concealed by a false back of the chair so that the surface of the device which engages the floor when used as a rocker will be substantially hidden when the device is returned to that position wherein the chair is stationary. This surface which becomes marred by contact with the floor would ordinarily be visible and the present arrangement greatly preserves the finished appearance of the chair.

Another object has been to embody a device in a chair by means of which the degree of recline may be changed from a stationary upright

position to a reclined position by a simple backward movement of the chair and to provide a spring element for the device which is capable of returning the device to its upright position when the back of the chair is lifted.

Another object has been to provide parts for the purpose of this invention which can be assembled entirely in the ordinary furniture factory by cabinet makers; there being few accessory metal parts.

It has been another object of my invention to provide a safety feature on the device so that a person sitting rocking, or reclining in the chair cannot tilt back far enough to overbalance the chair and fall over backwards.

Further objects and advantages of the invention will be readily apparent, to those skilled in the art, from the following description of the drawings in which:

20 Figure 1 is a perspective view looking up into the underside of a chair showing the adjustable rocker element as it appears when constituting the rear legs of a chair.

25 Figure 2 is a perspective view taken similar to Figure 1 in which the element is shown as it appears when in use as a rocker.

Figure 3 is a side view of a chair illustrating the rocker element when being utilized to constitute the rear legs, as in Figure 1.

30 Figure 4 is a side view illustrating a chair provided with the adjustable rocker element as it would appear when a person is sitting in it.

Figure 5 is an enlarged fragmentary sectional view taken on line 5—5 of Figure 1 showing a 35 rocker element in position as a rear leg.

Figure 6 is an enlarged view similar to Figure 5, in which the rocker element has been swung down into more inclined or rocking position.

Figure 7 is an enlarged fragmentary sectional view taken on line 7—7 of Figure 5 showing the manner in which the rocker element is pivotally secured to a chair.

With the exception of a false back 10, the body portion of the chair shown in the drawings is 45 constructed like an ordinary "easy" chair, comprising a base 11, arms 12, and appropriate cushions 13. The front legs, indicated at 14, are standard, being fastened to the base by screws (not shown) or other means.

50 The false back is constituted by an extension rearwardly of the two side rails of the base 11 beyond the line of the back cushion and a cross rail 15 which joins the two side rails at the rear of the chair. The rear surface of the chair and the sides are preferably upholstered just as an

ordinary easy chair. The rocker device is installed between the side rails.

The adjustment or rocker device comprises, generally, a pair of legs 16-16, a tie bar 17, a pair of pivot pins 18-18 and spring elements 19. The outline of the legs 16-16 is best illustrated in Figures 5 and 6. Each leg has a flat surface 20 upon which the chair rests when the adjustment device is being utilized to provide the higher position for the chair, a curved surface 21 upon which the chair is rocked from the high or stationary position into a lower position, and a slightly concave surface 22 upon which the chair rests when at its lower or rockable position.

Although not necessary, the concavity of the legs is preferred because it provides a two point contact for each leg and, consequently, a better base upon which the chair rests when it is in rocking position (Figure 4). Another cross rail 23, attached to and extending between the side rails of the base 11 within the false back, is provided as a stop or rest against which the rocker device abuts when in the high position (Figure 5).

The rocker element is pivotally mounted on the retainer pins 18 in the side rails of the base 11. Each leg 16 is drilled to provide a hole 25 through which a pivot pin 18 extends. A large flat head 26 on each pin is secured to the inner faces of the legs as at 27 by screws or other means. The extended ends of the pins are journaled in bushings 28 which are press fitted into holes in the side rails 11 of the base of the chair.

The pair of springs 19-19 are secured to the forward face of the cross rail 23 near both sides of the chair, by screws or staples. The springs are under compression between the cross rail 23 and the cross rail 17 on the rocker element. When the rocker element is in the stationary or upper position (Figure 5) the springs are relaxed, but when the chair is moved into the lower position (Figure 6), the spring is compressed. Thus when the rear of the chair is lifted from the floor the springs move the rocker element into the higher position.

From Figure 5, it will be noted that the pivot point is forward of the support surface 20 when the rocker device is set up in the high position with the legs engaging the rail 23. It will be noted that the rail 23 is directly above the leg surface 20 when the device is in the high position. This is provided so that the chair will not be pushed unintentionally into rocker position when a person sits down in the chair. From Figure 6, it will be noted that the pivot point is directly above the surface 22 when the chair is in the low or rocking position. This is preferred, because it provides a more solid base upon which the chair can be rocked.

In use, when a person wishes to move the chair into the lower or rocking position, it is only necessary to urge the chair rearwardly slightly. This

causes the chair to rock down and back smoothly on the curved surfaces 21 of the rocker element to a position of rest on the concave surfaces 22. The person then may tilt the chair back into a balanced reclined position (Figure 4) or may tilt back and forth in a rocking motion. A foot stool, as shown in Figure 4, although not necessary, aids materially in attaining a restful position in the chair.

Now, to return the chair to its stationary or higher position the rear of the chair is lifted from the floor. This permits the spring 19 to return the rocker element to the position wherein it provides the stationary rear legs for the chair.

Having described my invention, I claim:

1. In a chair construction of the type including a rigid seat and back and front legs; an adjustable unit pivotally mounted at the back of the chair, said unit providing leg structures each of which includes two supporting surfaces which surfaces are at different distances from the pivotal point; one of said surfaces, namely, the one which is closest to the pivotal point including a flat portion, a curved portion extending forwardly to the other surface; a cross rail embodied in the seat of the chair and constituting a supporting stop for the adjustable device when the device is in position with that surface most distant from the pivotal point engaging the floor and said back including portions extending downwardly and substantially concealing the adjustable unit.

2. A chair comprising a unitary seat, back, and front leg structure, a rear leg unit pivoted to the seat at the rear thereof, the legs of said unit respectively having flat surfaces angularly related to each other and at different distances from the pivot of the unit so as to provide alternative rear legs of different heights, and stop means on said structure at the rear of the pivot, said stop means adapted to be engaged by the legs of said unit for limiting rearward swinging movement of the rear leg unit and for supporting the rear legs by engagement therewith when said rear legs have been swung to rearward position.

3. A chair comprising a unitary seat, back, and front leg structure, a rear leg unit pivoted to the seat at the rear thereof, the legs of said unit having flat surfaces angularly related to each other and at different distances from the pivot so as to provide alternative rear legs of different heights, cooperating stop means on said unitary structure and said rear legs respectively, said stop means on the unitary structure being disposed to the rear of the pivot of said rear leg unit and adapted to limit rearward swinging movement of the unit whereby said rear legs are disposed in position with one set of flat surfaces engaging the floor and said unitary structure being adapted to rock on said pivot of the rear leg unit when the other set of surfaces are in engagement with the floor.

CARLYLE F. STREIT.
